UNITED STATES PATENT OFFICE.

HOWARD WILLIAM PIERCE, OF BUTTE, MONTANA.

PISTON.

Application filed February 23, 1923. Serial No. 620,826.

To all whom it may concern:

Be it known that I, HOWARD WILLIAM PIERCE, a citizen of the United States, and a resident of Butte, in the county of Silver Bow and State of Montana, have invented new and useful Improvements in Pistons, of which the following is a full, clear, and exact description.

This invention relates to pistons, primarily designed for use in internal combustion engines, but also suitable in any device requiring a reciprocating piston.

Usually in the use of reciprocating pistons it is found that one side of the piston carries a greater load than the other and consequently suffers from greater wear. When a piston becomes worn on one side there develops what is known as piston slap, which gives rise to a considerable wear of the cylinder. In some cases the piston slap may become so great that it is annoying to the operator of the engine or other device.

The general object of this invention is the provision of a simple and durable piston constructed with a detachable side wall adjustably mounted on the body of the piston so that the piston may be adjusted to any desired diameter either at the original setting up of the piston or after it has been partially worn.

This object is accomplished by constructing the piston with a detachable side wall section, forming integral with the body of the piston a lug for supporting the side wall section, and providing means for attaching the side wall section in different relative positions on said lug.

These and other objects of the invention will be more clearly understood from the following detailed description and accompanying drawings.

Figure 1 is a vertical section through the piston along the line 1—1, Figure 2, showing the piston construction;

Figure 2 is a horizontal section of the piston showing certain members spaced apart in order to show their construction.

Referring to the above-mentioned drawings, the invention includes a hollow body portion 10 formed with a plurality of webs 11, supporting a lug 12 extending transversely of the body portion. The head 14 of the lug 12 is hollow, as shown in Figure 1, and curved to conform to the wall of the piston. Elongated openings 13 extending in the line of the diameter of the piston is

formed in the head 14. A section 15 of the side wall of the piston is made detachable and has two webs 16 and 17 formed therein and spaced apart so that they will fit over the head of the lug 12. Openings 18 and 19 are provided in the webs 16 and 17, respectively, and are so positioned that they align with the elongated openings 13 in the head of the lug when the detached section 15 of the side wall is placed in position. The opening 18 is provided with an internal thread for receiving a bolt 20 which is projected through the openings in the lug and webs 16 and 17. This bolt serves to retain the section 15 of the side wall in position, completing the body of the piston. In order to fix the bolt 20 so as to prevent it working loose, an opening 21 is provided in the bolt for receiving a cotter pin or the like.

When the section 15 does not rest against the curved end of the lug 12, a shim 22 is provided for rigidly fixing the wall of the section 15 in the desired position relative to the body of the piston 10. These shims are usually made of bronze or some suitable material and may be constructed of any desired thickness, so that the section 15 may be spaced in any desired position relative to the body of the piston.

As shown in Figure 1, the head of the piston is of usual construction. A plurality of circumferential grooves 23 are formed in the piston head for receiving the piston rings. An opening 24 projects through the body of the piston for receiving the wrist pin 25.

In using a piston of this type after the piston has become partially worn the section 15 may be set relative to the body of the piston so as to give the original diameter. In order to fix the section 15 of the side wall in the desired position a shim 22 of proper thickness may be mounted between the head of the lug 12 and the section of the side wall. Such a construction is of value in that there is room for expansion due to heat without great distortion of the piston. In constructing pistons of this type it is possible to make the portion of the piston which is subject to the greatest wear of a different material from the body of the piston. The detached section may be replaced when it is damaged thus eliminating the necessity of discarding the whole piston.

If desired a piston of this type might be

constructed with two removable sections 15 located opposite one another. Such a construction would take care of wear on both sides due to the thrust of the connecting rod. 5 However, since the wear usually takes place on one side the preferred construction has been described and set forth in the preceding portion of this specification.

I would state in conclusion that while the 10 illustrated example constitutes a practical embodiment of my invention I do not limit myself strictly to the exact details herein illustrated since manifestly the same can be considerably varied without departing from 15 the spirit of the invention as defined in the appended claims.

Claims.

1. A piston comprising a hollow body having one side cut away and provided with 20 a transverse lug in said cut away portion, said lug having a hollow head and provided with alined elongated openings, a removable section having spaced and recessed webs provided with openings, said section fitting in 25 the cut away portion of the piston with its webs engaging the top and bottom of the lug, and a bolt passing through the openings of the head of the lug and the webs of the section.
2. A piston comprising a body having one 30 side recessed and provided with a transverse

lug in said recess, said lug being provided with a head having alined slots therein, a removable section having spaced and recessed webs provided with openings, one of which is screw threaded, and a bolt extending through the unthreaded opening of one of the webs, the slots of the head, and screwing into the threaded opening of the other web of the section. 35

3. A piston comprising a body having one side recessed and provided with a transverse lug in said recess, said lug having a head provided with alined slots, a removable section having spaced webs engaging the top and bottom of the head of the lug and each provided with an opening, a shim between the head of the lug and section, and a bolt passing through the openings of the web and the slots of the head of the lug. 40

4. A piston of the character described, comprising a body having one side cut away and provided with a member extending into the cut away portion intermediate its ends, a removable section closing the cut away portion and provided on its inner face with inwardly projecting members engaging the member of the body, and means for adjustably securing the members of the section to the member of the body. 45 50 55
